UNITED STATES PATENT OFFICE.

DAVID BIRCH, OF NEW YORK, N. Y.

NON-REFILLABLE BOTTLE.

1,142,230.

Specification of Letters Patent. Patented June 8, 1915.

Application filed May 17, 1913. Serial No. 768,318.

To all whom it may concern:

Be it known that I, DAVID BIRCH, a subject of the King of Great Britain, residing at New York city, in the county of New 5 York and State of New York, have invented new and useful Improvements in Non-Refillable Bottles, of which the following is a specification.

This invention relates to non-refillable bottles and has for its object to provide a means, whereby a bottle after being once filled cannot be refilled after the contents has been discharged.

Another object of the invention is the 15 provision of a simple, efficient and thoroughly reliable means which may be applied to bottles in general use, and which means when in place are so arranged as to render the bottle practically fool-proof.

20 To these ends the invention consists in the novel details of construction and combination of parts more fully hereinafter described and particularly pointed out in the claim.

25 Referring to the accompanying drawings forming a part of this specification in which like numerals designate like parts in all the views: Figure 1 is a side elevational view of the upper portion of a bottle neck and showing my invention applied thereto. Fig. 2 is 30 a longitudinal sectional view thereof. Fig. 3 is a plan view of one of the baffles. Fig. 4 is a cross sectional view thereof. Fig. 5 is a plan view of another one of the baffles. Fig. 6 is a cross sectional view thereof. Fig. 35 7 is a plan view of the spring, and Fig. 8 is a cross sectional view thereof.

Referring to the drawings in detail 1 designates the upper portion of the bottle neck, 40 provided with a series of exterior annular grooves or channels 2.

3 designates an enlarged sleeve provided with the interior grooves or channels 4, and 45 5 designates a cement filling which enters the grooves and which, when it becomes hardened, rigidly secures the sleeve to the neck of the bottle.

The sleeve has its interior wall tapered as at 6 to provide a seat for a weighted valve 7 50 and is shouldered as at 8 to provide a chamber 9 and again shouldered at its upper end as at 10, to provide a recess 11 adapted to receive a keeper 13 which is provided with a stem 14 that projects within the central 55 apertured portion 15 of the valve and acts

as a guide for normally insuring the proper seating of the valve when the bottle is in its upright position.

The upper wall of the sleeve is provided with a series of outlet openings 16 which communicate with the chamber 9 and these openings are adapted to be normally covered by means of a cap 17 which fits over the outer end of the sleeve. The cap is also provided with perforations 18 to correspond with the openings 16 and may be turned so as to bring its perforations into coincidence with the openings 16 when it is desired to remove some of the contents of the bottle. To prevent the removal of the cap from the 70 bottle it has a portion 19 on its side spun into a groove formed in the side of the sleeve as shown.

Located within the chamber 9 are spaced baffles 20 and 21 which are designed to render 75 the bottle fool-proof and thereby prevent the insertion of instruments into the bottle neck to manipulate the valve. These baffles are centrally perforated to permit the stem of the keeper 13 to be inserted therethrough, 80 and with relation to which they may turn. The baffle 20 is provided with a series of peripheral notches 22 and the baffle 21 is provided with a series of perforations 23.

A light spring 24 of suitable construction, 85 such as the spider-shaped one shown, is also located within the chamber 9 and engages with both the under surface of the baffle 21 and the top of the valve for normally seating the valve when the pressure of the liquid has been removed therefrom.

It will be observed that when the parts of my improvement are in their normal position as shown in Fig. 2, the valve completely 95 closes the entrance to the bottle, thereby rendering it practically impossible to refill the bottle, but when necessary to discharge the contents after the bottle has been originally filled, the cap 17 is first turned so that its perforations are brought into coincidence with the openings in the sleeve, then the bottle is tilted to the proper angle, thereby causing the valve under the pressure of the liquid to unseat itself. The liquid will then flow, passing around the valve, through the chamber 9 and on out through the openings in the baffles and sleeve. When the bottle is righted and the pressure of the liquid is relieved from the valve, the spring will cause 100 the valve to again be seated, after which the 105 110

cap is then turned so that its perforations will be brought out of coincidence with the openings in the sleeve.

It is obvious that those skilled in the art may vary the details of construction and arrangements of parts without departing from the spirit of my invention and therefore I do not wish to be limited to such features except as may be required by the claim.

10 What is claimed as new is:

In a non-refillable bottle a sleeve provided at its sides with outlet openings, a valve mounted within the sleeve, a keeper held in the sleeve and provided with a stem upon 15 which the valve is slidably mounted, baffles mounted upon the stem one baffle having an

annular rib which engages the other baffle whereby the major portions of the baffles are spaced from each other said baffles having in the vicinity of their peripheries openings 20 which lie at one side of the openings in the sleeve and a spring interposed between the valve and the innermost baffle and serving to hold the valve in a closed position in the sleeve and the baffles in frictional contact 25 with each other.

In testimony whereof I affix my signature in presence of two witnesses.

DAVID BIRCH.
